UNITED STATES PATENT OFFICE

CLAUDE A. CRIGER, OF JEFFERSON CITY, MISSOURI

COUNTER TOP

Application filed June 20, 1929. Serial No. 372,453.

This invention relates to a counter top designed primarily for use in connection with hotels, but it is to be understood that a counter top, in accordance with this invention may be employed for any purposes for which it is found applicable, and the invention has for its object to provide, in a manner as hereinafter set forth, a counter top having means for the storage of guest register cards and telegrams, as well as means for displaying advertising matter in a protective manner.

A further object of the invention is to provide, in a manner as hereinafter set forth, a counter top formed of a compartment body member, a slotted, apertured, opaque section and a series of transparent imperforate sections, and with the opaque and transparent sections seated in the body member. The opaque section and body member are formed preferably of materials of contrasting colors, preferably black and white marble respectively.

A further object of the invention is to provide, in a manner as hereinafter set forth, a counter top for the reception of register cards thereby eliminating the old cabinet or book registry system.

Further objects of the invention are to provide, in a manner as hereinafter set forth, a counter top which is simple in its construction and arrangement, strong durable, thoroughly efficient in its use, readily assembled, pleasing and distinctive in appearance and inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a top plan view of a counter top in accordance with this invention.

Figure 2 is a view looking towards one side edge thereof.

Figure 3 is a section on line 3—3 Figure 1.

Figure 4 is a section on line 4—4 Figure 1.

Figure 5 is a view looking towards one end edge thereof.

Figure 6 is a section on line 6—6 Figure 1.

Figure 7 is a section on line 7—7 Figure 1.

The counter top includes a body member 1 of rectangular contour. The width, length and height of member 1 are as desired. Preferably the member 1 is formed from a slab of white marble. The inner side edge of the member 1 is indicated at 2 and its outer side edge at 3.

The member 1 transversely thereof and at its center is formed with a rectangular compartment 4, and the bottom of which is provided with a pair of rectangular pockets 5, 6 arranged in spaced relation and endwise alignment. The pockets 5, 6 are disposed longitudinally with respect to the body member 1. Snugly fitting the walls of compartment 4, as well as being flush with the upper face of the body member 1, is the opaque section of the registry and which is in the form of a slab 7, preferably constructed of black marble. The slab 7 is formed between its transverse median and one end with a polygonal opening 8 in which is arranged a pen holder 9, the latter being supported upon the bottom of compartment 4. The slab 7 is furthermore provided with a pair of spaced, rectangular slots 10, 11 which register with the pockets 5, 6. The slot 10 in connection with the pocket 5 provides a compartment for the reception of telegrams. The slot 11 in connection with the pocket 6 provides a compartment for storing guest register cards.

The outer end wall of the compartment 4 is indicated at 12 and its inner end wall at 13. The inner end of slab 7 at its top is rabbed as at 14.

The body member 1 between the inner end 16 of slab 7 and inner side edge 2 is formed with a pair of spaced, closely arranged, rectangular, shallow, rear open top compartments 15, 16 adapted to receive advertising matter and which is protected by abutting, removable transparent panels 17, 18 prefer-

ably formed of beveled plate glass, and which close the top of such compartments.

The body member 1 at each side of compartment 4 is formed with a pair of open top compartments 19, 20 of rectangular contour to receive advertising matter. The outer end walls of compartments 19, 20 are spaced inwardly with respect to the outer end of slab 7. Each compartment 19, 20 has its bottom inclining downwardly from the inner end wall to the outer end wall of the compartment. With reference to Figure 6 the inclination of the bottom is shown. Figure 6 illustrates compartment 20 and its bottom at 21.

The upper face of body member 1 is cut away to provide combined wall and seat portions 22, 23 and 24. The portion 22 is common to compartments 4, 15 and 19. The portion 23 is common to compartments 15, 16 and the portion 24 is common to compartments 4, 16 and 21. A wall part 25 is provided and which forms the inner side walls of compartments 15, 16 and inner end walls of compartments 19, 20. The wall part 25 has a continuous rabbet 26 to provide a seat. The outer side wall and outer end walls of compartments 19, 20 are rabbeted to provide seats, and this structural arrangement is indicated in dotted lines in Figure 1, as at 27, 28, 29, 30 respectively.

The compartments 19 and 20 are closed by removable, transparent panels 31, 32 respectively and which preferably are formed of beveled plate glass. The panels 31, 32 protect the displayed advertising matter supported upon the inclined bottoms of compartments 19, 20.

The panels 17, 18, 31 and 32 are the transparent sections of the registry desk.

The panels 17, 18 abut and are mounted on the wall portions 22, 23 and 24, and in rabbets 14 and 26. The panel 31 is mounted in rabbets 26, 27 and 29 and on wall portion 22. Panel 31 abuts slab 7 and panel 17. The panel 32 is mounted in rabbets 26, 27 and 30 and on wall portion 24. Panel 32 abuts slab 7 and panel 18. Wall portion 23 is of less length than wall portions 22 and 24.

The outer side walls of compartments 19 and 20 are indicated at 33, 34 respectively. The outer end walls of compartments 19 and 20 are indicated at 35, 36 respectively. Extending outwardly from wall parts 23 and 24 to the outer end wall 12 of compartment 7 are wall forming parts 37, 38 which complete the side walls of compartment 7. The wall forming portion 23 extends from wall forming part 26 to the inner end wall 13 of compartment 7.

It is thought that the many advantages of a registry desk or counter in accordance with this invention can be readily understood, and although the preferred embodiment of the invention is as illustrated and described, yet it

is to be understood that changes in the details of construction can be had which will fall within the scope of the invention as claimed.

What I claim is:

1. A counter top comprising a body member having its upper face, centrally thereof, provided with a compartment, the bottom of said compartment being formed with a pair of pockets, and a slab completely filling said compartment and provided with a pair of slots registering with said pockets to provide a pair of spaced, open top compartments. 70

2. A counter top provided at a point between its transverse median and each end with a compartment, each wall of each of said compartments being rabbeted at its top, the bottom of each of said compartments inclining downwardly from rear to front, and transparent panels seated on said rabbets for closing said compartments. 80

3. A counter top comprising a body member having a compartment positioned centrally of its upper face, said body member further having a pair of opposed compartments interposed between the rear walls of the central compartments and the rear side of said body member, a slab seated in said central compartment and rabbeted at its rear marginal portion, and transparent panels for closing said pair of compartments, said 90 panels seating on said rabbets. 95

4. A counter top comprising a body member formed centrally thereof and between its longitudinal median and rear side with a pair of lengthwise opposed compartments, the rear wall of each of said compartments being rabbeted, the end walls of each of said compartments being of less height than the rear walls, a slab seated in said body member and providing the forward wall of each of said compartments, said slab being rabbeted at the rear marginal portion thereof, and transparent panels abutting each other, closing said compartments and seated on said rabbet and end walls. 100

In testimony whereof, I affix my signature hereto.

CLAUDE A. CRIGER.
